UNITED STATES PATENT OFFICE

WILLIAM J. FIEGEL AND WINFIELD S. ENDERICH, OF DETROIT, MICHIGAN, ASSIGNEES
TO BOHN ALUMINUM AND BRASS CORPORATION, OF DETROIT, MICHIGAN, A COR-
PORATION OF MICHIGAN

PUDDLING DEVICE

Application filed June 24, 1929. Serial No. 373,363.

This invention relates to puddling devices and has a primary object the provision of means for effecting a thorough agitation of the molten metal in the puddling crucible to mix the unmelted metal as the former is fed into the crucible and to remove all danger of the molten metal burning in the crucible.

A further object of the invention is to provide a rotatable agitator movable from a position within the molten metal to a position above the normal level of the same together with means automatically operable upon movement of the agitator to control the rotation of the same.

15 These and many other objects and advantages of the invention will become more apparent as the following description proceeds, particularly when reference is had to the accompanying drawings wherein,

20 Figure 1 is a side elevational view partly in section of a device constructed in accordance with the teachings of this invention;

Figure 2 is a front elevational view of the structure shown in Figure 1;

25 Figure 3 is a top plan view of a portion of the structure shown in Figure 1, and

Figure 4 is a fragmentary sectional view through a portion of the structure shown in Figure 1.

30 In the drawings wherein like reference characters designate corresponding parts throughout all views, the numeral 10 designates a support which may as illustrated be in the form of a wall provided with the openings 11 and 12 for a purpose hereinafter to be more fully described. On one side of the wall are the crucibles 13 adapted to receive metal to be melted and on the other side of the wall are the actuating mechanisms 14,

40 the latter being protected from the heat of the crucibles by the wall 10. If desired the crucibles may be arranged in groups of two, there being an actuating mechanism 14 associated with each crucible, since as shown in Figure 2 of the drawing, with this arrangement a single source of power may supply power to both of the actuating mechanisms.

45 It is to be clearly understood, however, that the crucibles and the actuating mechanisms 50 for the same may be arranged either in groups

as illustrated or may be mounted independently and operated independently as will be readily apparent.

Secured to the front face of the wall 10 is a supporting bracket 20 which provides a bearing for a shaft 21 on which is fixed a pulley 22. The pulley is driven by a belt 23 from any suitable source of power (not shown) and the shaft 21 extends into a gear housing 24 for driving reduction gearing of any desired character. The reduction gearing in turn drives a pinion 25 which meshes with a gear 26 on a shaft 27 and the gear 26 in turn meshes with a gear 28 on a shaft 29. The shafts 27 and 29 extend horizontally across the front face of the wall 10 in spaced relation to each other and are journaled in bearings 30 and 31 respectively, carried by the bracket 20. The shaft 27 is provided at its opposite ends with the eccentrics 32 for a purpose hereinafter to be more fully described, while the shaft 29 is adapted to drive the shafts 33 arranged at its opposite ends and projecting through the openings 11 in the wall 10 as clearly illustrated in Figure 1 of the drawing. It will be clearly understood that for an assembly of two crucibles there will be two openings 11 and two shafts 33, the two shafts being driven by the same driving shaft 29.

Fixed to the inner face of the wall 10 is a plate 35 having the projecting ribs 36, one of these ribs being provided for each crucible.

Pivoted as at 37 to each rib 36 is a supporting member 38 which as illustrated may preferably be in the form of a bell crank lever. Suspended from one leg 39 of this lever is a weight 40 forming a counter-balancing means to partially balance the weight of an agitator 41 supported as at 42 on an extension 43 of the other leg 44 of the bell crank lever. This agitator is mounted for movement from a position within the crucible and below the normal level of the molten metal, as shown in Figure 1 of the drawing, to a position above the normal level of the molten metal, and this movement of the agitator is effected by an oscillation of the bell crank lever 38 about its pivot 37. For oscillating the lever 38 there is provided a link 45 which extends through

the opening 12 in the wall 10. Fixed to the inner end of the link 45 is a U-shaped strap 46 which forms a guide for a cross head 47 which is pivotally connected as at 48 to the leg 44 of the bell crank lever. A spring 49 abuts at its one end against the end of the link 45 and at its other end against the face of the cross head to yieldably retain the cross head at the extreme inner end of the U-shaped strap 46.

10 The outer end of the link 45 is provided with the hook recess 50 adapted to be engaged by a pin 51 carried by the eccentric 32, the eccentric being keyed to the shaft 27 as at 15 52. Obviously rotation of the shaft 27 rotates the eccentric 32 and the pin 51 causing the link 45 to be periodically drawn outwardly through the opening 12 to rock the bell crank lever about its pivot. Thus as the shaft 27 is 20 rotated the agitator is oscillated from a position within the crucible to a position above the same, this oscillation of the agitator being continued until the link 45 is rendered inoperative in a manner about to be described.

25 Slidably mounted for longitudinal movement in the bracket 20 is a bar 55 which is arranged parallel to and slightly below the shaft 27. A rod 56 is journaled in an opening 57 in the wall 10 and extends to a point 30 adjacent the crucible 13 where it is provided with an actuating handle 58 whereby the same may be rotated. The outer end of the rod 56 is bent upwardly as at 59 and rearwardly as at 60 for engagement with the bar 35 55. Obviously when the rod 56 is rotated or oscillated the bar 55 will be reciprocated as will be clearly apparent by reference to Figures 1 and 2 of the drawing. The bar 55 is adapted to be moved from its retracted 40 position where its free end clears the link 45 to a position where its free end crosses the path of movement of the link 45 to thus limit downward movement of the link when the latter is actuated by its eccentric connection 45 to the shaft 27. By reference to Figure 2 of the drawings it will be noted that the bar 55 shown at the right is in its retracted position where its free end clears the link 45 permitting movement of this link in the manner 50 above brought out. The bar 55, however, on the left as viewed in Figure 2 is in its extended position where its free end crosses the path of movement of the link 45 to thus limit downward movement of this link.

55 In the operation of this portion of the device when the shaft 27 is rotated the link 45 is actuated to oscillate the bell crank lever and the agitator 41, the latter being moved from a position within its crucible to a position 60 above the same as will be readily apparent. When, however, the handle 58 is moved to shift the bar 55 into its extended position, downward movement of the link 45 is limited so that the link 45 is not actuated by the eccentric 32 regardless of the continued

rotation of the latter. Thus, when the bar 55 is shifted to its operative position the link 45 is held in its outermost position with the agitator 41 above the crucible 13.

70 The agitator 41 is provided with a shaft 65 and fixed to this shaft within a housing 66 is a pinion 67 adapted to be driven by a bevelled pinion 68 keyed to a stub shaft 69 journaled in a bearing 70 supported by the portion 43 of the bell crank lever. The shaft 69 is universally connected as at 71 to the shaft 33 whereby rotation of the shaft 33 effects a 75 rotation of the agitator.

80 The shaft 33 extends through the opening 11 and is slidably and rotatably mounted in a bearing 72 fixed to an arm 73. The arm 73 is provided with a sleeved extension 74 journaled in the bearing 31 whereby the bearing 72 is mounted for rocking movement about the shaft 29. The arm 73 supports at its other end a bearing 75 which 85 rotatably journals the sleeve 76 of a driving clutch member 77. Keyed to the other end of the sleeve 76 is a pinion 78 mounted for meshing engagement with a gear 79 fixed to the end of the shaft 29. Thus, whenever the shaft 29 is rotated the driving clutch member 77 is rotated, the sleeve 76 rotating within the bearing 75.

90 As brought out before the shaft 33 is slidably and rotatably mounted in the bearing 72 and this shaft is also slidably and rotatably mounted in suitable bearings within the sleeve 76. Thus, the driving clutch member 77 may be rotated without imparting rotation to the shaft 33. At its free end the shaft 33 is provided with the key-way 80 adapted to slidably but non-rotatably receive the hub 81 of a driven clutch member 82. The driven clutch member is normally held in engagement with the driving clutch member by a spring 83 which abuts at its one end against the hub 81 and at its other end against the collar 84 fixed to the shaft 33. The inner end of the key-way terminates in a shoulder 85 which limits longitudinal movement of the hub of the driven clutch member and forms a means whereby upon longitudinal movement of the shaft 33 the driven clutch member may be moved out of engagement with the driving clutch member. Thus, whenever the agitator is moved vertically to its position above the crucible, the shaft 33 is moved outwardly longitudinally and the driven clutch member is moved out of engagement with the driving clutch member to thus disconnect the drive between the driving shaft 29 and the driven shaft 33.

95 For yieldably supporting the bearing 75 there is provided an arm 90 having its base fixed as at 91 to the upper edge of the bracket 20. The arm 90 extends upwardly and forwardly to provide the portion 92 which extends over the bearing 75 and in 100

spaced relation to the same. Suspended from the portion 92 of the arm 90 is a U-shaped strap 93, the legs 94 of which terminate in the lateral extensions 95. A similar U-shaped strap 96 has its base secured at 5 97 to the bearing 75 and has its legs 98 provided with the lateral extensions 99. The U-shaped straps are arranged in telescopic engagement with each other and a spring 100 surrounds both of the U-shaped straps and abuts at its opposite ends against the lateral extensions 95 and 99. Thus the bearing 75 is yieldably suspended from the portion 92 of the arm 90 as will be clearly apparent by reference to Figure 1 of the drawing.

From the above it is believed that the structure and operation of the invention will be clearly apparent. In the embodiment of 20 the invention shown there are two crucibles 13 and therefore two actuating mechanisms 14 both of which are driven by shafts 27 and 29 from the pulley 22. It is to be clearly understood, however, that the crucibles 25 may be arranged in groups of two as illustrated or may be arranged in larger groups or singly, depending entirely upon the size of the plant in which the device is installed. Considering then the operation of one of the 30 agitators in connection with its crucible, it will be noted that the agitator is movable from a position within the crucible and adjacent the bottom of the same to a point above the crucible and above the normal 35 level of the molten metal in the crucible. In use heat is applied to the crucible in any desired manner to melt the metal therein and during the operation of the device unmelted metal is constantly added to the 40 molten metal in the crucible and mixed with the molten metal. Thus, with the shafts 27 and 29 rotating, the shafts being driven from the pulley 22, and with a certain amount of molten metal in the crucible 13, 45 shavings or the like are fed into the top of the crucible. The rotation of the shaft 27 rotates the eccentric 32 to actuate the link 35 and thus rock the bell crank lever 38. This rocking of the lever 38 effects an oscillation of the agitator 41 so that the agitator 50 is moved from a position adjacent the base of the crucible to a position above the normal level of the molten metal therein.

During its oscillation the agitator is periodically rotated by virtue of the engagement 55 of the clutch members 77 and 82. Thus the agitator is moved to a position within the crucible and below the normal level of the molten metal and is then rotated while in this position. Continued operation of the device moves the agitator to a position above the normal level of the molten metal at which time the rotation of the agitator is stopped so that the molten metal clinging to the blades 60 of the same will not be thrown outwardly

around the crucible. In its downward movement the agitator forces the unmelted metal down toward the bottom of the crucible and by virtue of its rotation effects a mixing of this unmelted metal with the molten metal. 70

The actuation of the agitator may be stopped by shifting the bar 55 into the path of movement of the link 45 to prevent operation of this link by the eccentrics 32. Thus the actuation of each agitator may be controlled at the will of the operator and each agitator in its operation will effect a thorough mixing of the unmelted metal with the molten metal within the crucible. 75

While the invention has been described with considerable detail, it is to be clearly understood that the description is for the purposes of illustration only and is not definitive of the limits of the inventive idea. The right is therefore reserved to make such changes in the details of construction and arrangement of parts as will fall within the purview of the attached claims. 80 85

What we claim as our invention is:

1. In a puddling device, a crucible, an agitator, means for rotating said agitator, and means independent of the rotating means for the agitator for moving said agitator in an arcuate path from a position within said crucible and below the normal level of the molten metal therein to a position above the normal level of the molten metal. 90 95

2. In a puddling device, a crucible, an agitator, a pivotal mounting for said agitator, means for oscillating said agitator mounting about its pivot, means for rotating said agitator, and a common means for driving said oscillating means and said rotating means. 100

3. In a puddling device, a crucible adapted to contain molten metal, an agitator, means for rotating said agitator while the same is within the crucible, means for moving said agitator to a position above the normal level of the molten metal, and means operable 105 upon the actuation of said last mentioned means for rendering said rotating means inoperative. 110

4. In a puddling device, a crucible, an agitator movable from a position within the crucible to a position exterior of the same, means for rotating said agitator, and means automatically operable to render said rotating means inoperative when said agitator is moved to its position exterior of said crucible. 115 120

5. In a puddling device, a crucible, an agitator movable from a position within the crucible to a position exterior of the same, a driven shaft for rotating said agitator, a driving shaft, a clutch for coupling said driving shaft to said driven shaft and means for disengaging said clutch upon movement of said agitator to its position exterior of said crucible. 125 130

6. In a puddling device, a crucible, an agitator, a pivotally mounted support for said agitator, and means for moving said support about its pivot to move said agitator from a position within said crucible to a position exterior of the same.

7. In a puddling device, a crucible, an agitator, a pivotally mounted support for said agitator, and means for moving said support about its pivot to move said agitator from a position within said crucible to a position exterior of the same, said means including a rotatable shaft, an eccentric on said shaft, and a link engageable with said eccentric and yieldably connected to said support.

8. In a puddling device, a crucible, an agitator, actuating means for said agitator, means for supporting said agitator within said crucible, a link for oscillating said supporting means, and means to move the agitator to a position exteriorly of the crucible for rendering said link inoperative.

9. In a puddling device, a crucible, an agitator, actuating means for said agitator, a pivotally mounted support for said agitator, a link connected to said support for oscillating the same, means for actuating said link, and means for rendering said link inoperative independently of the operation of said link actuating means.

10. In a puddling device, a crucible, an agitator, a pivotally mounted support for said agitator, a link connected to said support for oscillating the same to move said agitator to positions within and exteriorly of the crucible, means for actuating said link, and means for rendering said link inoperative independently of the operation of said link actuating means, said last mentioned means including a bar movable to a position to limit movement of said link in one direction, and means for moving said bar.

11. In a puddling device, a crucible, an agitator, a pivotally mounted bell crank lever for supporting said agitator within said crucible, means for moving said bell crank lever about its pivot to move said agitator out of said crucible, and counter balancing means secured to said bell crank lever for partially balancing the weight of said agitator.

12. In a puddling device, an agitator, a shaft for rotating said agitator, a driving clutch member slidably and rotatably mounted on said shaft, a driven clutch member keyed to said shaft, and means for moving said shaft to selectively effect an engagement or disengagement of said clutch members.

13. In a puddling device, an agitator, a shaft for rotating said agitator, a driving clutch member slidably and rotatably mounted on said shaft, a driven clutch member keyed to said shaft, a spring for urging said

clutch members into engagement with each other, and means for imparting longitudinal movement to said shaft to effect a disengagement of said clutch members.

14. In a puddling device, a crucible, an agitator, means for supporting said agitator for movement from a position within said crucible to a position exterior of the same, means for moving said agitator to either of the said positions, a driven shaft for rotating said agitator, said shaft being mounted for longitudinal movement upon movement of said agitator from either of said positions to the other, a drive shaft, and means for clutching said drive shaft to said driven shaft, said means being controlled by the longitudinal movement of said driven shaft.

15. In a puddling device, a crucible, an agitator, means for supporting said agitator for movement from a position within said crucible to a position exterior of the same, means for moving said agitator to either of the said positions, a driven shaft for rotating said agitator, said shaft being mounted for longitudinal movement upon movement of said agitator from either of said positions to the other, a drive shaft, and means for clutching said drive shaft to said driven shaft, said means being controlled by the longitudinal movement of said driven shaft, and including a driving clutch member rotatably mounted on said driven shaft, and a driven clutch member keyed to said driven shaft and movable therewith into and out of clutching engagement with said driving clutch member.

16. In a puddling device, a crucible, an agitator, a pivotally mounted support for said agitator, and means for swinging said support whereby to alternately move said agitator automatically in an arcuate path to positions within and exteriorly of the crucible.

In testimony whereof we affix our signatures.

WILLIAM J. FIEGEL.
WINFIELD S. ENDERICH.
